ABSTRACT

A magnetically enhanced coaxial cable of the type having a center conductor, a dielectric spacer around the center conductor and a conductive shield around the dielectric spacer, said magnetic enhancement comprising a thin layer of circumferentially oriented uniaxial anisotropic magnetic material having high conductivity and high permeability adapted to transmit wave energy and conventional current without being switched or reoriented. The magnetic enhancement provides an increase inductance and current carrying capacity without corresponding increases in time delay and other losses associated with magnetic loading.

**MAGNETICALLY ENHANCED COAXIAL CABLE
WITH IMPROVED TIME DELAY
CHARACTERISTICS**

BACKGROUND OF THE INVENTION

This invention relates to coaxial transmission cables for use in transmission of both conventional current and electromagnetic waves. More particularly, this invention relates to a magnetically loaded transmission cable which has greater current carrying capabilities than previously known cables of equal size or alternatively the novel magnetically loaded transmission cable is capable of being made smaller in size and volume than previously known cables without causing increases in losses or time delay normally accompanying magnetic loading.

Heretofore, it was known that magnetically loading a coaxial transmission cable would increase the inductance of the line. As the inductance increases, characteristic impedance and the time delay increases in conventional coaxial cables. Heretofore, it was desirable to increase the inductance by magnetic loading to decrease attenuation even though magnetic loading introduces hysteresis and eddy current losses and causes time delays.

Magnetic loading materials spaced in the dielectric of coaxial cables are described in U.S. Pat. Nos. 2,787,656; 2,929,034 and 2,727,945. These and other magnetic loading teaching are generally concerned with high resistance and high permeability ferrites which by their structural nature are large or relatively thick and are not applicable for use in microminiature cables. Thin film magnetically coated conductors have been employed in plated wire memory planes such as those shown in U.S. Pat. No. 3,460,114, however, such rigid planes are generally concerned with reducing the characteristic impedance of an unshielded insulated memory wire. Plated memory wires are not uniformly shielded and are designed to switch from one state to another by coupling magnetic fields.

There has long been a need to reduce the size and weight of flexible coaxial cables. Our co-pending application Ser. No. 266,345 filed June 26, 1972 for "Improved Coaxial Cable" solves many of these problems. These and prior art structures were accompanied by increases in time delay. Coaxial cable for high speed computers and communications equipment require minimized time delays as well as miniaturization. Major computer manufacturers and coaxial cable manufacturers have recognized this need but have not miniaturized conventional coaxial cables by magnetic loading. Since computer advances are often accomplished through faster operations embodied in solid state devices, the need for faster propagation of electrical pulse energy has become almost as important as miniaturization of the circuitry.

BRIEF SUMMARY OF THE INVENTION

The present invention provides a coaxial cable having increased characteristic impedance achieved through magnetic loading which increases the inductive reactance and decreases the attenuation, however, the increase in inductive reactance is not accompanied by the usual expected increase in time delay. The means employed to achieve magnetic loading do not increase the eddy current and hysteresis losses or other losses which would detract from the use of the novel

coaxial cable as a miniaturized high frequency coaxial transmission cable.

A principle object of this invention is to reduce the size and weight of a coaxial cable without changing its characteristic impedance or increasing losses and time delay.

Another object of the present invention is to minimize time delay of coaxial cables while increasing the inductive reactance.

Another object of the present invention is to provide a method for producing a series of microminiature coaxial cables having new and desirable attenuation and time delay characteristics.

Another object of the present invention is to provide means for conducting larger amounts of conventional current without increasing the overall size of a coaxial cable.

Accordingly, there is provided a conventional coaxial cable structure comprising a center conductor and an outer shield separated by a dielectric spacer. The center conductor is further provided with a thin film of circumferentially oriented uniaxial anisotropic magnetic material having a thickness much less than the diameter of the center conductor but thicker than the skin depth thickness at the desired highest frequency of the operation. Means supplying electrical energy to the center conductor are preferably limited to an operational level or direction which prevents switching of magnetic orientation, thus permitting the minimum delay time in wave propagation. These and other features of the present invention will be set forth in greater detail in the following description.

DESCRIPTION OF THE DRAWINGS

FIG. 1 is a transverse sectional view of a miniaturized coaxial cable constructed in accordance with teachings of this invention;

FIG. 2 is a longitudinal section view of a miniaturized coaxial cable constructed in accordance with the teachings of this invention;

FIG. 3 is a simplified equivalent network circuit of a conventional coaxial cable;

FIG. 4 is a typical B vs. H curve for square loop high permeability magnetic material;

FIG. 5 is a schematic curve showing current density vs. distance from the center of a center conductor;

FIG. 6 is a simplified equivalent network circuit of the new coaxial cable.

DESCRIPTION OF THE PREFERRED EMBODIMENT

FIGS. 1 and 2 show a coaxial cable 10 constructed in accordance with a preferred embodiment of this invention. The cable comprises a center conductor 11 of conductive material such as copper, copper-beryllium or other high strength conductive alloys. A thin conductive coating of magnetic material 12 is conductively attached to the center conductor 11 directly or to an extremely thin base conductive layer (not shown) on the center conductor 11.

The thin layer of magnetic material 12 is preferably circumferentially oriented with an easy magnetization axis transverse to the direction of wave propagation. Conversely, the hard magnetization axis is axially aligned with the direction of wave propagation to assure the preferred mode of operation of the invention. It has been found that uniaxial anisotropic Ni-Fe films

500A to approximately 15,000A thick provide a desirable oriented film for the preferred embodiments hereinafter explained.

A preferred method of providing the desired uniaxial anisotropic orientation is to plate the desired magnetic layer 12 onto the center conductor 11 in the presence of a strong circumferentially oriented magnetic field such as that which occurs when a strong d.c. conduction current is passed through the center conductor 11. The center conductor 11 may be annealed and then placed in the presence of strong circumferential field while the magnetic layer 12 is cooled from above its recrystallization temperature. Reheating and reorienting may be necessary when stress relieving a plated center conductor 11 or when hot processes are employed to attach the dielectric spacer 14.

A dielectric spacer 14 surrounds the magnetically coated center conductor 11 and a continuous conductive shield 13 surrounds the dielectric spacer 14. The shield 13 may be protected by an insulating layer or jacket 16.

It was discovered that the novel coaxial transmission cable did not operate in a manner to be expected by the addition of a magnetic loading material. The operating characteristics of the coaxial cable shown in FIGS. 1 and 2, both with and without magnetic loading materials may be defined by equivalent circuit formulas. A simplified equivalent network circuit for a conventional coaxial cable is shown in FIG. 3.

The series inductance L of an equivalent tee section coaxial transmission cable has been defined by

$$L = \frac{\mu}{2\pi} \log \frac{D}{d}$$

the shunt capacity C by

$$\frac{1}{C} = \frac{1}{2\pi\epsilon} \log \frac{D}{d}$$

the characteristic impedance Z by

$$Z = \sqrt{\frac{L}{C}} = \frac{1}{2} \sqrt{\frac{\mu}{\epsilon}} \log \frac{D}{d}$$

the attenuation α by

$$\alpha = \frac{R}{2} \sqrt{\frac{C}{L}} + \frac{G}{2} \sqrt{\frac{L}{C}}$$

and the time delay T by

$$T = \sqrt{LC} = \sqrt{\frac{\mu}{\epsilon}}$$

where μ is the permeability of the dielectric, ϵ is the dielectric constant of the dielectric spacer, D is the inside diameter of the outer shield, d is the outside diameter of the center conductor, R is the series resistance, C is the shunt capacitance and G is the shunt conductance.

The values in a standard original coaxial cable may be designated by sub- σ notation and values of prior art magnetically loaded coaxial cable may be designated by sub- r notations. Adding a very thin layer of magnetic material to the center conductor will increase the inductance L_σ to L_r without measurably changing the spacing of the elements, the dielectric constant ϵ of the dielectric spacer 14 or the shunt capacitance C.

Formula (1) indicates that the inductance L, increases with an increase in resultant permeability μ_r . Formula (2) indicates that the shunt capacity C is inversely proportional to D/d and directly proportional to the dielectric constant ϵ . Formula (3) indicates that characteristic impedance Z_r increases with an increase in inductance L_r. Formula (4) indicates that attenuation α_r decreases with an increase in inductance L_r as the first term of formula (4) is large compared to the second term. Formula (5) indicates that time delay T_r increases with an increase in inductance L_r and effective permeability μ_r .

A piece of standard construction coaxial cable having an impedance of 17 ohms was found to have a time delay T_o of approximately 1.5 nanoseconds per foot. An increase of the resultant μ , over μ_o by a factor of five would ordinarily increase both Z_r and T_r by the square root of five. Applicants have been able to so increase Z_r without a corresponding increase in T_r.

In one series of tests the time delay of a seventeen ohm coaxial cable appeared to be unchanged or reduced even though the inductance L_r and characteristic impedance Z_r were increased. A piece of the novel coaxial cable was altered to change the circumferentially oriented easy axis of the uniaxial anisotropic layer of thin magnetic material 12 to a partially isotropic layer. The time delay T_r of the altered sample almost doubled. For comparison purposes, it has been established by test and calculations that a seventeen ohm coaxial cable can be increased to 50 ohms by magnetically loading the cable. Ordinarily magnetic loading would increase the time delay from 1.5 nanoseconds per foot, to over 4.0 nanoseconds per foot. The time delay of the magnetically enhanced cable constructed according to the present invention remained at approximately 1.5 nanoseconds per foot, however, when the same coated center conductor was partially annealed to partially destroy the desired magnetic orientation the time delay increased to over 2.5 nanoseconds per foot.

It was discovered that 80% Ni - 20% Fe Permalloy plated on copper beryllium center conductors to a thickness of 8,000A to 10,000A in a manner which provides a circumferentially oriented magnetic easy axis, when made into the novel coaxial cable, increased the characteristic impedance Z_r without an appreciable increase in time delay T_r over T_o. Initial results indicate that the time delay may be as low as or below that obtained for coaxial cables without magnetic loading.

The properties of uniaxial anisotropic material may be enhanced by first coating a flash layer of copper on the center conductor. It is believed that the copper or other conductive undercoat aids in maintaining uniform anisotropy and masks structural defects in the center conductor. Thin films 500A to about 15,000A thick have been made which have easy axis and hard axis orientation. It may be desirable, as in plated wire memories, to restrict the magnetostriction effects to a minimum as usually occurs in Permalloy films having approximately 80% nickel. Films which have the above described circumferential easy axis orientation may be made by plating, vacuum deposition and sputtering in the presence of a circumferentially oriented magnetic field. Other film techniques such as cladding, rolling, evaporation, drawing, chemical deposition and suspension deposition may require post operative annealing in an induced magnetic field.

Nickel iron alloys and other conductive magnetic materials which have crystalline grain structure may be coated on the center conductor and then cold drawn so as to create a preferred desired oriented magnetic field.

The plated thin films were deposited or treated in a magnetic field so that the preferred orientation was circumferential and the film displayed high anisotropy. The clad and drawn nickel iron wires, known to have a crystalline grain structure, were oriented mechanically through the process of drawing. Annealing the drawn wire does not have to destroy the high anisotropy developed mechanically, thus, drawn wire may be more stable for commercial purposes. Solid magnetic drawn wires display the desirable permeability increase but are not as conductive as clad wires. While the special crystal orientation is not well understood, it is presumed that an apparent effective internal magnetic field is present as a result of interaction of grain crystals and the high effective internal field. This magnetic field is present at the wall of the center conductor which forms the wave guide. There appears to be a faster phase change as a result of the oriented magnetic field and the time delay is decreased (increase in phase velocity).

Another feature of the present invention requires that the thin layer of magnetic material 12 be relatively conductive so that the radial electrical field E at the boundary of the center conductor be continuous, as will be explained. Permalloy type thin films are considered to be high permeability, low resistance films, whereas ceramic ferrites are considered to be high resistance, high permeability materials which do not conduct conventional current.

The dielectric material 14 can be any low loss dielectric preferably having a dielectric constant in the range of $\epsilon = 1.2$ to 3.5 . The dielectric constant for air is 1.0 and for foamed plastics may be as low as 1.3 , however, Teflon which is desirable for many uses is 2.1 . Materials known to be used in coaxial cables such as Mylar, polyethylene, polypropylene and other polyolefins are also useful in the present novel cable. The shield 13 is made from a conductor which has low loss at operating frequencies. Copper braid is sometimes employed because it is known to act as a closed shield below 1000 megahertz. Solid copper in the form of film, wire, foil or foil supported on insulating tapes may be employed. It is desirable that the shield 13 be conductive and at least twice the skin depth thickness at the upper frequency of operation as is the case for coaxial cable outer shields.

The outer insulation layer 16 may be any typical electrical insulation and may be applied as a tape either with or without the shield 13.

High permeability materials usually have high eddy current and hysteresis losses. Ferrites have been employed as magnetic loading materials in coaxial cables because the B vs H loop is narrow indicating that low hysteresis losses are to be expected. FIG. 4 illustrates an open B vs H loop of the type obtained with thin films or Permalloy materials, where B is the flux density and H is the magnetizing force intensity. The permeability μ of a material is defined as $\mu = B/H$. The slope of the curve is substantially horizontal in the saturation region, and substantially vertical in the unsaturated region. It can be seen that the incremental permeability $\mu \Delta$ will increase if the magnetizing force H switches the saturation region from negative to positive saturation.

The incremental permeability $\mu \Delta$ of uniaxial anisotropic films may be held substantially constant at very small values (about 5 gauss per oersted, thus it is possible to transmit pulse power in the novel coaxial transmission cable by remaining on a horizontal portion $\mu \Delta$ of the B vs H curve, such as operating between point 21 and 22 on the curve without incurring time delay increases as would be incurred if operating at maximum permeability.

It has been found that 75 ohm novel transmission cable may be operated in a conventional mode with very high frequency pulse power surges up to three fourths of a watt without switching the magnetic orientation or incurring hysteresis or eddy current losses.

The novel coaxial cables may be used within the usual power ranges for standard coaxial cables without encountering undesirable effects.

If the aforementioned formulas (1), (2) and (3) are combined it can be shown that $Z = \sqrt{L/C}$ and

$$Z = \frac{1}{2\pi} \sqrt{\frac{\mu}{\epsilon}} \log \frac{D}{d} \quad (6)$$

As is well known, when the value of D/d approaches 3.59 , attenuation α approaches a minimum and Z at minimum attenuation is approximately 77 ohms. Heretofore, it has been the practice to make some small coaxial cable having 50 , 75 , and 100 ohm impedances and having center conductors of 0.008 , 0.010 and 0.010 inches diameter respectively. Such coaxial cables employing a Teflon dielectric require D/d ratios of 2.3 , 3.4 and 5.3 respectively when no magnetic loading is employed. Prior attempts to decrease the cable size without magnetic loading, increased the characteristic impedance and attenuation. Prior attempts to decrease attenuation were directed to an increase in inductance L and characteristic impedance Z through magnetic loading without a decrease in cable size.

Employing the present invention and maintaining the same center conductor as employed in the above mentioned prior art 50 , 75 and 100 ohm coaxial cables, the D/d ratio of the new novel 50 , 75 and 100 ohm coaxial cables may be reduced as follows: for 50 ohm cable D/d of 2.3 is reduced to 1.4 , for 75 ohm cable D/d of 3.5 is reduced to 2.2 and for 100 ohm cable, D/d of 5.3 is reduced to 3.0 . These figures are rounded representing a resultant or effective permeability μ_r of 5 and a dielectric constant 68 for Teflon of 2.1 .

It will be understood that the values of μ_r and ϵ may be changed and the desired impedance values of 50 , 75 and 100 ohms maintained. As the D/d ratio is reduced and approaches unity the maximum values of μ_r required to achieve the desired impedance are obtained as follows. If ϵ is 1.0 as in air, μ_r approaches 5.3 for 50 ohm cable; 12.2 for 75 ohm cable and 28 for 100 ohm cable. If 68 is 1.6 as with foamed plastic, μ_r approaches 8.3 for 50 ohm cable; 23.4 for 75 ohm cable and 68.8 for 100 ohm cable. If ϵ is 2.1 as with Teflon μ_r approaches 11.2 for 50 ohm cable; 37.6 for 75 ohm cable and 126 for 100 ohm cable. Permalloy thin films which are oriented by a magnetic field or by cold drawing of the type employed are capable of achieving values of μ_r below the above five (the value employed for a preferred embodiment). Other magnetic thin film materials having the range of permeabilities described and having the above-mentioned desire uniaxial circumferential orientation may be employed.

Reduction of the ratio of D/d while maintaining the impedance Z constant permits microminiature coaxial cable to be designed. The inside diameter D of the shield can now be reduced without increasing time delay or other losses which normally accompanied magnetic loading impedance increases. Had the novel coaxial cable been available heretofore it could have been employed in aircraft and spacecraft electronics systems to decrease weight of the coaxial cables by up to 50 percent and further decrease the size and weight of the electronic hardware.

It is known that conventional current is displaced to the outside annular area of a conductor as frequency increases. FIG. 5 shows schematically how the current density increases exponentially toward the outer diameter of the center conductor 11. At the center 23, where the radius $r=0$, the current density is substantially zero at high frequency and rises to a maximum at the outer diameter 24 of the center conductor. Due to skin effect phenomenon the current density is believed to fall sharply at the boundary and increase exponentially again in the thin layer of magnetic material 12, rising to a maximum at the outside 25 of the magnetic material and then falling to zero. The skin depth thickness δ may be defined by the equation:

$$\delta = \sqrt{\frac{1}{\pi f \mu \sigma}} \quad (7)$$

where f is the frequency of operation, μ the maximum permeability of the conductor, and σ is the conductivity. In a preferred embodiment, the skin depth thickness for the magnetic material and the copper conductor were estimated to be 0.62 microns and 4.6 microns thick respectively at 350 megahertz. The actual thickness of the magnetic layer was approximately 10,000A or 1.0 micron. In the preferred embodiment explained hereinbefore the thin layer of magnetic material was thicker than the skin depth thickness. As frequencies increase the skin depth thickness will decrease, and if the thin layer of magnetic material is not reduced accordingly, attenuation of the electric field will result.

The thin layer of magnetic material 12 is preferably conductive and conductively attached to the center conductor 11 so that the radial electric field is continuous. When the electric field is continuous at the boundary, the conduction current is divided inversely proportional to the skin depth thicknesses of the two materials. It can be shown that highly conductive Permalloy having a small skin depth thickness will conduct a much larger amount of conduction current at high frequencies than the percentage increase in diameter of the center conductor. Since this phenomenon is true for one conductive layer of material having a different resistance, it is true for multiple layers of material having different resistances which are conductively connected or arranged in a continuous electric field to independently support conductive skin layers.

Not only does the thin layer of magnetic material conduct a portion of conventional current, but it enhances conduction of some form of wave energy. Without changing the conductivity of the magnetic material in a piece of novel cable, it was annealed partially destroying the circumferential orientation of the easy axis. As a result of the annealing the characteristic impedance $Z_R = \sqrt{L_r/C}$ increased which is attributed to an increase in aforementioned permeability μ and

μ_r , however, the time delay increased more than can be accounted for by any possible increase in permeability. The propagation of the wave energy is enhanced by the aforementioned circumferential orientation of the uniaxial anisotropic magnetic material. It may be possible that the partial annealing caused the shape of the B vs H curve to change, thus the operation on a vertical slope region of the B vs H curve causes hysteresis losses, flux changes and time delays which did not occur when operating on a saturation portion of the curve of square loop material described in FIG. 4.

Another explanation for the decrease in time delay T is made with reference to FIG. 6 showing a schematic network representation of the new coaxial cable. The 15 shunt arm 26 of the equivalent Tee network was found to have an inductive reactance 27 in series with the shunt capacitance 28 which lowers the resonance point or cut off point compared to coaxial cables without the thin layer of magnetic material. At high frequencies 20 above the cut off point, usually above 20 megahertz where fast rise time of sub nanosecond pulse power is operable, the inductive reactance 27 (X_L) is very large and tends to cancel out the capacitive reactance 28 (X_C). Above the cut off frequency the shunt arm 26 appears highly inductive so that the center conductor 11 is substantially isolated from the shield-return 13. When isolation occurs the time delay T is no longer equal to $\sqrt{LC}$ and the speed of propagation begins to 25 approach the speed of light as is achieved in an open conductor, however, the skin effect losses and radiation losses which accompany open conductors have been reduced to those associated with standard coaxial cables.

Part of the current conducted in the layer of magnetic material may be forced into a helical path which helps to explain the increase in inductive reactance and the high magnetic field.

Another desirable feature of employing Permalloy Ni - Fe materials is to achieve reduced phase distortion. At 40 high frequencies Permalloy acts as a magnetic damper providing a desirable roll off characteristic. This characteristic substantially attenuates the frequencies above the operating frequencies which would otherwise provide phase distortion.

While this invention has been described with respect to particular embodiments employing a particular high anisotropy substantially circumferentially oriented magnetic material it is apparent that other magnetic materials can be found which have the desirable characteristic described hereinbefore. The coaxial transmission cable and method for reducing time delay and attenuation have been described as best available theoretical analysis will now permit. Other embodiments for reducing the size of coaxial cables for high frequency use without increasing time delay and attenuation will become apparent to those skilled in this art.

we claim:

1. In a communication system having means for generating high frequency electro magnetic energy pulses representing intelligence, a coaxial cable for transmitting said pulses, and means for receiving said pulses, said cable comprising in combination:

an electrical center conductor,
a magnetizable material at the outside surface of said center conductor,
said magnetizable material being magnetically oriented to provide a magnetic field which is substan-

2. A coaxial cable as set forth in claim 1 wherein said magnetizable magnetic material is magnetically oriented to provide an easy axis of magnetization in a direction which is substantially circumferential around the outside of said center conductor. 20

3. An improved flexible miniaturized coaxial cable of the type employed in transmitting very high frequency pulses having magnetic loading comprising:

a flexible center conductor having an outside diameter d ,
said flexible center conductor comprising a conductive magnetic material at the outside diameter d having a high permeability creating an increased resultant permeability μ_r in the cable,
said conductive magnetic material having a crystalline grain structure and having an easy axis of magnetization at least partially oriented to provide an internal magnetic field in a circumferential direction,
flexible dielectric material spacer means surrounding said center conductor having an outside diameter D_r and a dielectric constant ϵ , and
a flexible conductive shield supported on and sur-

a flexible conductive shield supported on and surrounding the outside of said dielectric spacer means and having an inside diameter D whereby the characteristic impedance of said improved flexible cable $Z = 1/2\pi \sqrt{\mu_r/\epsilon} \log D_r/d$ is increased by an increase in μ_r through magnetic loading and the time delay T_r is increased by an amount less than $\sqrt{\mu_r/\epsilon}$ by providing said internal magnetic field. 45

4. An improved flexible coaxial transmission cable of 50 the type set forth in claim 3 wherein said conductive magnetic material comprises nickel and iron.

5. An improved flexible coaxial transmission cable of the type set forth in claim 4 wherein said conductive magnetic material comprises Permalloy having very low magnetostrictive characteristics. 55

6. An improved flexible coaxial transmission cable of the type set forth in claim 3 wherein said center conductor comprises a thin layer of magnetic material greater than 500A and less than 15,000A thick and is thin enough to maintain uniaxial anisotropy in a circumferential direction. 60

7. An improved flexible coaxial transmission cable of the type set forth in claim 3 wherein said conductive magnetic material comprises a thin layer having a thickness which is greater than the skin depth thickness at the frequency of operation. 65

8. An improved flexible miniaturized coaxial cable as set forth in claim 3 further characterized in that said center conductor comprises a very good conductive magnetic material center and an outside layer of conductive magnetic material having a preferred magnetic field oriented in a circumferential direction.

9. An improved flexible coaxial transmission cable for use in the transmission of very high frequency pulses of the type having magnetic loading for decreasing attenuation by increasing the inductance L_o and the characteristic impedance Z_o , comprising:

a flexible inner center conductor of low resistance material having an outside diameter d ,

a flexible outer shield of low resistance material surrounding said center conductor and having an inside diameter D ,

a flexible dielectric spacer disposed between said center conductor and said shield, said elements forming a flexible coaxial cable having a characteristic impedance $Z_o = \sqrt{L_o/C}$ and a time delay $T_o = \sqrt{L_o C}$, where C is the shunt capacitance,

a layer of flexible circumferentially oriented high permeability magnetic material formed on the outside of said center conductor, said elements now forming a coaxial cable having a resultant characteristic impedance $Z_r = \sqrt{L_r/C}$ where the resultant inductance $L_r > L_o$, and the resultant time delay T_r of very high frequency pulses is substantially less than $\sqrt{L_r C}$.

10. An improved flexible coaxial transmission cable as set forth in claim 9 wherein said layer of high permeability magnetic material is electrically conductive nickel-iron having a thickness between 500A to 15,000A and is uniaxial anisotropic.

11. An improved flexible coaxial transmission cable as set forth in claim 10 wherein said layer of circumferential oriented magnetic material and said center conductor form concentric conduction paths for high frequency pulse current concentrated in a skin effect pattern at high frequencies.

12. An improved flexible coaxial transmission cable as set forth in claim **11** wherein the current flow in said conduction paths is substantially proportional to the conductivity of the conduction path.

13. An improved flexible coaxial transmission cable for use in the transmission of very high frequency pulses comprising:

a flexible inner center conductor of low resistance material having an outside diameter d_1 ,
a flexible outer shield of low resistance material sur-

rounding said center conductor and having an inside diameter D_1 ,

a nonmagnetic dielectric spacer between said conductor and said shield, and
a layer of magnetic material formed at the outside of said center conductor and having a high permeability.

said center conductor and having a high permeability and an easy axis of magnetization oriented in a circumferential direction,

said layer of magnetic material providing a path for the conduction of very high frequency pulse energy, whereby said coaxial cable is rendered capable of transmitting more energy at higher wave propagation rates than conventional coaxial cables.

11

14. An improved flexible coaxial transmission cable as set forth in claim 13 wherein said layer of magnetic material is a low magnetostrictive Permalloy plated over a plated conductive base on said center conductor.

15. An improved flexible coaxial transmission cable as set forth in claim 13 wherein the usual D/d ratio for unloaded coaxial cable is reduced by at least thirty per-

12

cent without a change in the characteristic impedance Z by the addition of said layer of magnetic material.

16. An improved flexible coaxial transmission cable as set forth in claim 15 wherein the D/d ratio is reduced by decreasing the inside diameter D_r of said outer shield and the thickness of said wave-sustaining dielectric spacer.
